(57) **CLAIM**

The ornamental design for a gaming machine, as shown and described herein.

DESCRIPTION

FIG. 1 is a first front perspective view of a gaming machine of our new design.

FIG. 2 is a second front perspective view of the gaming machine of FIG. 1.

FIG. 3 is a front view of the gaming machine of FIG. 1.

FIG. 4 is a rear view of the gaming machine of FIG. 1.

FIG. 5 is a right side view of the gaming machine of FIG. 1.

FIG. 6 is a left side view of the gaming machine of FIG. 1.

FIG. 7 is a top view of the gaming machine of FIG. 1; and, FIG. 8 is a bottom view of the gaming machine of FIG. 1. The broken lines shown on the gaming machine form no part of the claimed design.

1 Claim, 8 Drawing Sheets(56)
